UNITED STATES PATENT OFFICE.

ARTHUR J. DORITHY, OF SPRINGFIELD, ILLINOIS.

DESIGN FOR A NAME-PLATE.

46,566.

Specification for Design. Patented Oct. 20, 1914.

Application filed May 9, 1914. Serial No. 837,587. Term of patent 7 years.

To all whom it may concern:

Be it known that I, ARTHUR J. DORITHY, a citizen of the United States, residing at Springfield, in the county of Sangamon and State of Illinois, have invented a new, original, and ornamental Design for Name-Plates, of which the following is a specification, reference being had to the accompanying drawing, forming part thereof.

The design, which is illustrated in the annexed drawing, comprises a pictorial repre-

sentation of an oil filter, partially in section; and an ornamental border surrounding the pictorial representation of the filter.

I claim:

The ornamental design for a name plate as shown and described.

ARTHUR J. DORITHY.
